UNITED STATES PATENT OFFICE

2,680,191

PUNCH PRESS ILLUMINATING DEVICE

Walter Ernst, Dayton, Ohio, assignor to The Commonwealth Engineering Company of Ohio, Dayton, Ohio, a corporation of Ohio.

Original application September 15, 1949, Serial No. 115,901. Divided and this application October 17, 1950, Serial No. 190,481.

1. Claim. (Cl. 240—2)

1 This invention relates to lighting or illuminating arrangements, and particularly to arrangements of this nature for use in connection with machine tools, such as presses and the like.

In a press of the type employed for forming articles, as well as in many other types of machine tools, there is a working space in which the work is operated as by punches and dies, or by forming members, or by cutting tools. The working space in machines of this nature, particularly heavy presses, is generally almost completely surrounded by the structure of the machine, thus leaving the space rather poorly lighted under ordinary circumstances. This is a disadvantage in that there is a chance for the operator to become injured or for workpieces or tools in the machine to become damaged because of conditions that would be observed under sufficient light.

Having the foregoing in mind, the principal object of the present invention is to provide an illuminating arrangement for the working space of machine tools, such as presses and the like, which will overcome the difficulties referred to.

A still further object of this invention is the provision of an illuminating means for the working space of a press or the like which is readily adjustable, so that the illumination is always directed to the proper place in the said working space.

A still further object is the provision of an illuminating arrangement for presses and the like so constructed that operating switches and the like can be incorporated therein, thus leading to a compact and efficient arrangement.

In general the objects of this invention are obtained by mounting a tubular light source in front of the working space of the machine and then movably positioning a reflector behind the light source so the reflector can be adjusted to direct the light to the proper location. A bracket supports and houses the illuminating means and reflector and can be used for supporting switches and the like which are utilized in controlling the operating of the machine.

This application is a division of my application Serial No. 115,901, filed September 15, 1949, and assigned to the same assignee as the instant application.

The foregoing objects and other objects and advantages of my invention will become more apparent upon reference to the following description taken in connection with the accompanying drawings, in which:

2 Figure 1 is a front elevational view of a hydraulic press having an illuminating arrangement according to this invention;

Figure 2 is an enlarged view looking directly at the front of the press where the illuminating means is mounted;

Figure 3 is a perspective view showing the illuminating means;

Figure 4 is a transverse section taken on line 4—4 of Figure 3;

Figure 5 is a perspective view showing the means for adjusting the position of the reflector associated with the illuminating means; and

Figure 6 is a sectional view indicated by line 6—6 on Figure 4 showing one manner in which the reflector can be pivotally mounted relative to the tube.

Referring to the drawings somewhat more in detail, the press shown in Figure 1 may comprise a bed 10, the spaced uprights 12, and a head 14. The head includes a motor having a ram 16 to which is attached platen 18 which also supports a blankholder 20. The working space of the press is indicated at 22 between blankholder 20 and bed 10 and is adapted for supporting a plurality of dies or other work members of different shape and configuration, as indicated by the dash outlines at 24.

According to the present invention, a rail or bracket 26, better illustrated in Figures 2 and 3, is mounted between uprights 12 in front of the working space, as by screws 28. Bracket 26 is generally hollow and mounted therein is an elongated tubular illuminating element 30 which may be a filament type lamp or a fluorescent or a neon tube, any of which are satisfactory for providing illumination. The tube 30, as will be seen in Figure 6, may comprise an end part 32 receivable in a socket 34 mounted on the end of the bracket.

In order to maintain the surface of the tube as clean as possible, the front end of the bracket 26 is preferably closed, as by the transparent or translucent cover element 36. This may comprise plastic or glass, although a plastic material is usually to be preferred because of its resistance to breakage.

Positioned behind tube 30 is a reflector element 38 which may have its end parts mounted about socket 34, as indicated at 40 in Figure 6, so as to permit tilting of the reflector about the axis of the tube 30, thereby to direct the light from the tube toward the most advantageous position in the working space of the press.

55 A lever 42 which is attached to reflector 38

extends out of a slot in the top of bracket 26 and is engageable by a detent arrangement 44, which provides for a plurality of different operative positions of the lever and reflector. This detent mechanism may comprise spaced spring fingers or spring strips, as may be seen in Figure 5, and is a convenient and inexpensive manner of providing this feature of adjustability.

In general, the arrangement of the tube and reflector as described will provide for general illumination of the working space with the reflector further providing a somewhat increased illumination over a selected area or zone within the working space, so that that part which must be most closely observed will be the best lighted.

The bracket 26 is made somewhat larger than is necessary for housing the tube and reflector and comprises a transverse channel arrangement 46 on the operator's side within which push-button stations, as at 48, may be provided for controlling the operation of the press. This results in a convenient manner of mounting the push-button stations or switches and also positions them where they will be convenient for the operator to manipulate.

Other switches or push-button stations which are less frequently employed, such as those which determine that type of cycle the press will operate, may be mounted on the uprights 12 at the ends of the bracket, as at 50, as will be seen in Figure 2. Those switches, however, which are to be operated on every cycle of the press are preferably located on the bracket 26, as described.

From the foregoing, it will be seen that my invention provides for a relatively simple, inexpensive, but nevertheless highly efficient arrangement for providing for illumination of the working space of a machine tool. The arrangement is such that it provides not only general lighting, but localized lighting as well, where increased illumination is desirable.

The net result of utilizing my invention is to make the operation of machine tools less hazardous and more rapid with the assurance that a better product will result because it can be better observed during operation.

The invention has been particularly described in connection with a hydraulic press, but it will be understood that it is adapted for use in connection with other types of presses, as well as

4
with other types of machine tools and the like having a working space that requires illumination.

It will be understood that this invention is susceptible to modification in order to adapt it to different usages and conditions, and, accordingly, it is desired to comprehend such modifications within this invention as may fall within the scope of the appended claim.

10 I claim:

In a press an illuminating device of the type described comprising: an elongated box-like hollow housing open along one side, a tubular lighting element in the housing, base members inside the ends of the housing to receive and support the ends of said lighting element, an adjustable reflector in said housing on the side thereof opposite the opening in said housing, said reflector having its ends journalled on said base members so as to be adjustable about the axis of said lighting element, means to adjust said reflector comprising a transverse slot in the upper surface of said illuminated housing, a rod-like handle member secured to said reflector and extending through said slot, a detent arrangement including a plurality of notches along each side of said slot and engageable with said handle member, thereby selectively locking said handle member in a plurality of positions, and said housing being provided with a compartment extending lengthwise thereof inside the wall opposite the said opening, said compartment providing space to receive wiring and switches forming a part of the control system of the press.
